UNITED STATES PATENT OFFICE.

ISIDOR BRACH, OF PHILADELPHIA, PENNSYLVANIA.

CIGAR MOLD AND LIFTER.

SPECIFICATION forming part of Letters Patent No. 740,622, dated October 6, 1903.

Application filed December 8, 1902. Serial No. 134,351. (No model.)

To all whom it may concern:

Be it known that I, ISIDOR BRACH, a citizen of the United States, residing at Philadelphia, in the county of Philadelphia and State of

5 Pennsylvania, have invented certain new and useful Improvements in Cigar Molds and Lifters; and I do declare the following to be a full, clear, and exact description of the invention, such as will enable others skilled in the art to which it appertains to make and use the same.

My invention relates to improvements in cigar molds and lifters for lifting the bunches from the matrix-cells thereof; and it consists 15 in the peculiar construction and combination of devices hereinafter fully described and claimed.

The object of my invention is to effect improvements in the construction of the mold 20 and to provide the same with flexible bunch-lifters, which are disposed longitudinally in the matrix-cells, are secured at one end, and are adapted to be pulled by their opposite ends and caused to assume an approximately 25 straight form, and thereby readily lift the bunches from the matrix-cells without danger of breaking the bunches or injuring the form thereof.

In the accompanying drawings, Figure 1 is 30 a perspective view of a cigar-mold embodying my improvements, parts being shown removed and parts in section to disclose the interior construction. Fig. 2 is a detail longitudinal sectional view of the same. Fig. 3 is a similar transverse sectional view of the 35 same.

The base-section 1 of the mold is provided in its upper side with a series of transversely-disposed matrix-cells 2 of suitable size and 40 shape and in which the bunches are formed. The matrix-cells are open at each end and are adapted to be closed at their smaller pointed ends by a bar 3, which is secured to one side of the base-section. On the opposite side of the base-section is a bar 4, which is adapted to close and to uncover the larger ends of the matrix-cells, the said bar being pivoted at one end to one side of the base-section, as at 5. The base-section is further 45 provided with suitable catches 6, which are adapted to engage the pivoted bar when the latter is in position to close the ends of the

matrix-cells and to secure the said bar in the said closed position, the usual studs 6 projecting upwardly from the end portions of 55 the base-section.

The upper section 7 of the mold is of the usual construction, has the followers 8 adapted to enter the matrix-cells of the base-section, and is provided near its ends with openings 60 9, adapted to be engaged by the studs 6 when the upper section is placed on the base-section, the said studs and openings coacting to secure the upper section on the base-section, as will be understood, and to cause the followers 8 to enter the upper side of the matrix-cells and coact with the latter in molding or forming the bunches, which are composed of small pieces of tobacco suitably moistened in the manner well known to those skilled in the 70 art to which my invention relates.

It is of great practical importance to facilitate the operation of removing the bunches from the matrix-cells after the bunches have been formed and to avoid breaking the 75 bunches or altering the shape thereof. To effect this object, I have provided the bunch-lifters 11, which are made of suitable flexible material or fabric. In practice I find that tape is a very suitable material to be used 80 for making the bunch-lifters; but I do not limit myself in this particular. Each bunch-lifter is disposed longitudinally and adapted to lie in the lower side of one of the matrix-cells, has one of its ends secured to the bar 85 3, and has its opposite end projecting outwardly from the larger open end of the matrix-cell, which is adapted to be closed by the pivoted bar 4. The latter is closed while the bunches are being formed. It is then opened, 90 the upper or top section 7 having been first previously removed from the base-section 1, and to remove the bunches from the cells without injuring the bunches it is only necessary to draw outwardly on the flexible 95 bunch-lifters to cause the same to straighten, and in so doing to lift the bunches out of the matrix-cells, as will be readily understood. The flexibility of the bunch-lifters enables the same to lie snugly in the bottoms of the 100 matrix-cells and to conform exactly to the shape thereof, so that the required shape may be given to the bunches.

From the foregoing description, taken in

connection with the accompanying drawings, the construction and operation of the invention will be readily understood without requiring a more extended explanation.

5 I do not desire to limit myself to the precise construction and arrangement of devices herein shown and described, as it is evident that modifications may be made therein without departing from the spirit of my invention 10 and within the scope of the appended claims.

Having thus fully described my invention, what I claim as new, and desire to secure by Letters Patent, is—

15 1. A cigar-mold, having a base-section provided with matrix-cells, open at each end, a relatively fixed bar closing one end of each of said matrix-cells, and a pivoted bar adapted to form a closure for the other end of each of said cells, said bar being pivoted at one end 20 to the mold, substantially as described.

25 2. A cigar mold, having a base-section, provided with a plurality of matrix-cells which open at each end, a relatively fixed bar forming a closure for one end of each of said cells, flexible bunch-lifters each extending longitudinally through one of the cells and having end portions to extend from the ends thereof, one end of each of the bunch-lifters being attached to said bar, and a bar to form a closure for the other ends of the said cells, 30 said bar being pivoted at one end of said mold, substantially as described.

3. A cigar-mold having a base-section provided with matrix-cells, a relatively fixed bar adapted to close one end of the cells, a removable bar to close the opposite ends of the cells, and flexible bunch-lifters attached at one end to the first-mentioned bar, said flexible bunch-lifters being adapted to lie in and extend longitudinally through the cells, and having end 35 portions to extend from the open ends thereof, substantially as described.

In testimony whereof I have hereunto set my hand in presence of two subscribing witnesses.

ISIDOR BRACH.
